[57] ABSTRACT

This invention can be used as an accessory to many different types of machines, mainly cut-off saws. It makes it possible to cut a quantity of material to different lengths in one operation per set-up, compared to one length per set-up in past inventions. The gauge operates by pushing the material to be cut alongside the guide bar, up to the desired stop. By pushing the material against the guide bar and side of the desired stop-pin, thus depressing the undesired stop-pins into the housing. The stops can be positioned anywhere within the guide bar, and can be turned within 360 degree circumference to suit the size of material being cut, drilled, etc., or to fit into grooves, holes or recesses in the material.

FIG. 1

FIG. 2

MULTIPLE STOP

This invention relates to being an accessory gauge (jig), which may be used with many different types of machines, mainly cut-off saws (radial arm saw). The most used jig now is a block fastened on with a clamp to a stop bar. Past inventions have emphasized fast set-ups and measurements, but can only cut one length per set-up. If several lengths have to be cut at one time, the set-up and measurements have to be changed. This procedure is time consuming and troublesome. Often two or more different lengths have to be cut out of one piece. For example: door headers, sizes 24 inch, 26 inch and 32 inch, have to be cut out of an 84 inch piece. Sometimes 100 pieces of each of the above mentioned sizes have to be cut at the one time.

For example: a person has to pick up the 84 inch piece, cut off one piece 32 inch, lay down the pieces left over, pick up the left over pieces and cut off one piece 26 inch, lay them down on a different place, and finally pick up the left over pieces and cut the 24 inch piece, handling it three hundred times and using a lot of space and time. I have found that time and space can be saved by being able to cut different lengths at the same time without having to change the set-up of the gauge as in my invention.

FIGS. 1 and 2 in the drawing illustrate the embodiments of my invention and are described below:

FIG. 1 is a front view of the assembled invention.

FIG. 2 is a section cut through the centre of a type A Stop.

The gauge illustrated comprises a channel 1, which is fastened to the work table or cross-slide of a machine, or to the machine itself by using bolts or screws. It also serves as guide rail for the material to be cut or drilled, and many more uses. The Stops 2, can be slid in on the end and placed in different positions as desired, by tightening a set screw 6 with an Allen wrench, thus pushing it tight against the front of the channel and locking it securely into place.

The type A Stop consists of a retractable stop pin 3, a spring 4, a plug 5 which closes the hole. The hole is of cylindrical shape drilled from the back of the Stop 2. (housing). It is narrower in the front so the pin 3 cannot slip out completely, and serves also as pin guide. 6 is a set screw for fastening the Stop 2. into any desired

position within the channel (guide bar).

The type B Stop, first stop in FIG. 1, is necessary if the lengths to be cut differ by less than one inch. It is adjusted by turning it inside the channel within a 360° circumference into the desired position. The type A Stops can also be turned into different positions to suit the size of material to be cut or to fit into grooves, holes or recesses in the material.

The material used for the gauge can differ to suit the application whether it is stationary or portable. On stationary gauges, hard good quality steel should be used because it is supported by the machine or work table. The material used for a portable gauge may need to be lighter and could be of good quality aluminum, or strong hard plastic. The stops could be of a variety of different shapes other than round also the stop-pins could be different to suit a specific application.

The gauge operates by pushing the material to be cut alongside the guide bar, up to the desired stop. By pushing the material against the guide bar (channel) and the side of the desired stop-pin thus depressing the undesired stop-pins into the housing, the stop-pins reposition themselves automatically when material is removed.

25 The embodiments of the invention in which an exclusive property or privilege is claimed are defined as follows:

1. A gauge for use with machines for duplicating a plurality of different lengths or locations in material per set up, comprising in combination a length of channel including an open front side, a plurality of pinguides slideably engageable within said channel, a set screw in said pinguide reacting between said pinguide and front side of channel to detachably and adjustably clamp said pinguides in said channel, said pinguides include at least one retractable pin mounted therein, a spring in said pinguide for said pin, normally biasing said pin to a position extending from said front side of channel but permitting said pin to move into said pinguide by compressing said spring when material is pushed against said pin, said pins reposition themselves automatically when material is removed, said pinguides being rotatable through 360 degrees within said channel for position adjustment of said pins.
